UNITED STATES PATENT OFFICE.

LEWIS H. SONDHEIM, OF NEW YORK, N. Y.

LEAD-PENCIL.

1,125,890.

Specification of Letters Patent.

Patented Jan. 19, 1915.

Application filed December 3, 1910. Serial No. 595,535.

To all whom it may concern:

Be it known that I, LEWIS H. SONDHEIM, a citizen of the United States, residing at New York city, borough of Manhattan, in the county and State of New York, have invented a new and Improved Lead-Pencil, of which the following is a full, clear, and exact description.

The present invention relates to that type of pencil in which an elongated lead has sliding movement in its sheath and is to be fed forwardly, as its point is used up, by a follower; and the object of the invention is to provide a pencil of the general type referred to, but greatly improved as regards the follower.

The improved follower is characterized itself across the bore of the sheath, in response to a lever movement imparted to it, when it is not required to be released to feed the lead forwardly.

Structurally the follower comprises a member of a size and shape that by being rocked will range across the bore in a jammed position, or range lengthwise of the bore to slide longitudinally thereof. The jamming element bears against interior surfaces presented either by the integral material of the sheath or by a tubular pusher forming a lining and thus constituting part of the wall of the bore adjacent to the follower.

The invention will be particularly described hereinafter, in connection with illustrated examples of its practical embodiment, and then defined as to scope in the appended claims.

Reference is to be had to the accompanying drawings, in which—

Figure 1 is a longitudinal section of a pencil in which my invention is embodied. Fig. 2 is an enlarged view of a part of the pencil showing the follower and a pusher which is appurtenant thereto in the preferred forms of my invention, the said parts being shown in the locked position; Fig. 3 is a transverse section, enlarged; Fig. 4 is a transverse section showing a modification; Fig. 5 is an enlarged, fragmentary, sectional view of the follower and pusher of Figs. 1, 2 and 3 in unlocked position; Fig. 6 is an enlarged top view of the form of separate pusher employed in the construction shown in Figs. 1, 2, 3 and 5. Fig. 7

is a similar view of the form of pusher employed in the construction shown in Fig. 4; Fig. 8 is a longitudinal section showing a further modification; Fig. 9 is a transverse section showing a follower used alone, without the separate pusher; Fig. 9^a is a longitudinal sectional view of the device shown in Fig. 9; and Fig. 10 is a transverse section showing a further modification of the follower, which may be employed without a pusher as shown.

The invention in its preferred form comprises a tubular sheath or holder, preferably of wood having a longitudinal bore to receive a lead, a slot reaching into the bore, and a follower member movable longitudinally in the bore and rockable to a jammed position against wall portions in the interior of the sheath. In jamming, the follower may press at one point directly against a wall portion presented by the integral material of the sheath while an opposite point on the follower may bear either directly against a wall portion presented by another point of the sheath approximately opposite the first point of bearing, or may bear against a wall portion presented by a pusher, as hereinafter explained.

Referring to the accompanying drawings A is the sheath or holder whose external form is similar to that of an ordinary wooden pencil. It has the longitudinal bore B and a slot C, communicating therewith, which slot is of less width than the diameter of the bore. The lead b moves (with a small amount of friction at its forward end) in the bore B. A tubular pusher D, Figs. 1, 2, 3, and 5, is adapted to move freely in the bore B and has the opening d, narrow at its forward end d¹ and widened at one side as at d² (see Fig. 6) or widened on both sides as at d² and d³ (see Fig. 7).

E is the lever follower, preferably in the form of an elbow or bell crank lever, which extends from the outside of the holder through the slot C and the opening d into the pusher D, and preferably consists of a flat piece of metal, having the long arm E¹ and the short arm E² and having the notch e by which it may be raised when in the locking position shown in Figs. 1 and 2. The follower lever E has attached to

it or formed upon it, the wider part or protuberance e^2 at such side thereof as will correspond when in position to the widened part d^2 of the opening d , or it may have such wider parts e^2 and e^3 on both sides (as shown in Fig. 4) which then will fit into opening d^2 and d^3 (Fig. 7). The greater the total frictional surface of the parts e^2 and e^3 , with which they contact with the wall of 10 the bore, the more security will be had against the lead point being accidentally pushed rearward.

It is obvious that the follower-lever when used without a pusher (as in the modification shown in Figs. 9 and 9^a) will itself be a means to push the lead forward, the principal function of the pusher used in the preferred form being that of steadyng the follower-lever when the latter is in an unlocked position, and of facilitating its forward movement and especially its rearward movement (effected by pressure upon the lead point) by guarding it from being casually tilted into a partially locked position 25 by the direct bearing of the lead upon same during such movement.

In practice the follower lever E is first inserted in the slot d of the pusher D and rocked to the position shown in Fig. 5, in which the forward part of the arm E^1 will rest in the narrow part d^1 of the opening d , and abut against the top of the pusher at the forward end of said opening, while the part e^2 will abut against the upper inside 30 surface of the pusher, thus limiting a further rocking or forward tilting of said follower lever when pressure is applied to same to move the follower forward. The pusher D with the follower lever in this position is then inserted in the rear end of the bore B of the sheath, the lever sliding along the slot C , until the lead rests upon the front end of the pusher D . It will be understood that the lever E although ordinarily separable 35 from the pusher D , is prevented by the sheath from so separating while the pusher is in the bore B . The protruding arm of the lever E is then pulled backward and downward into the position shown in Fig. 2. This will cause the rounded top of the thick part or protuberance e^2 to project slightly 40 through the opening d and to press against the upper side of the wall of bore B , while the bottom part of said part e^2 and the end 45 of the part E^2 of the lever will press against the lower side or wall of the pusher, pressing said pusher against the wall of the bore B at the bottom and binding both lever and pusher immovable in said bore, while the 50 longer end of the lever E enters the slot C and only the upper edge of the same with the notch e remains visible. To move the lead forward the arm E^1 of the lever is 55 raised by inserting the finger nail in the notch e to rock said lever until said lever arm E^1

abuts against the wall at the forward end of the opening d^1 , when it and the lead may be easily pushed forward and then secured by pulling the lever down. When it is desired to retract the lead, the lever is raised and the lead pushed back from the front of the pencil, carrying the follower backward with it.

The long arm of the lever on the outside of the sheath gives sufficient power to produce the needed jam; it also gives a sufficient hold to the fingers, when it is in position to advance the lead, to overcome any temporary obstruction which may exist in the bore; while said lever is almost completely hidden in the sheath while at rest.

In Fig. 8 I show the pusher D^1 with an opening d^4 on its lower side, thus allowing the lower portion of the arm E^5 of the follower, and the lower portion of the widened part e^5 , which in this construction are both slightly elongated, to project through the tubular pusher D^1 , and thus establish a direct bearing (upon two opposite sides of the wall of bore B) of the said lower portions of E^5 and e^5 on the one side, and the upper part of the portion e^5 on the other side.

In Fig. 9 I show a follower lever E^3 with a thicker part e^4 (corresponding with e^2 previously described) interlocked in a wooden sheath without the use of a separate appurtenant pusher. When the lever in this construction is raised the part E^3 will itself serve to directly push the lead. In Fig. 10 I show a modification of the follower lever. In place of the part e^4 which extends almost the length of the part E^3 of the lever, a rounded projection e^6 , is produced (preferably by stamping) on the lever part E^3 which will take the place of the upper rounded end of the part e^4 in pressing against one side of the sheath, while the end of the part E^3 will press against the other side or wall.

In the form shown in Figs. 1, 2, 3, and 5, and that shown in Fig. 4, the lower end of the follower when worked, engages the pusher D , which in these instances forms a lining for the sheath and becomes the wall of the sheath, as it then is held immovable relatively to the sheath and transfers thereto the received pressure of the follower, and therefore structurally as well as functionally it is in effect the wall of the sheath as far as the action of the lower end of the follower is concerned when binding or jamming transversely of the bore.

In some forms of the invention the inner portion of the lead advancing device, through which the jamming and consequent locking of said device is effected, consists of a single member only, while in other forms said inner portion consists of a pusher combined with a part of the lever. In either case the rocking movement of the outer arm

jams the inner part of the device in the bore, and I consider this a material feature of my invention.

Having thus described my invention, I 5 claim:

1. In a pencil the combination with a sheath, having a bore adapted to receive a lead and a slot communicating with the bore, of a lead advancing device of which a portion is located within the bore and is wider than the slot, and having an arm, adapted to be rocked, extending through the slot to the outside of the casing, the inner part of said device being movable longitudinally within the bore, but being adapted to be locked against longitudinal movement by being jammed between approximately opposite portions of the walls of said bore by the rocking of the outer arm, substantially as 20 described.

2. A pencil comprising a sheath having a bore accommodating a lead and a longitudinal slot extending from the bore to the outside, a rockable follower having a member 25 in said bore and a separate pusher slideable in said bore, the said follower engaging the pusher and forming when rocked a lever lock for said pusher.

3. A pencil comprising a sheath having a bore accommodating a lead and a slot extending from the bore to the outside, a rockable follower in the form of a bell-crank lever, of which one member extends to the outside and one member lies within the sheath, and a separate tubular pusher lying within the bore of said sheath engaged by the follower, and locked by the said follower when the latter is rocked, to cause the inner member to range crosswise.

4. A pencil in which is comprised a sheath having a longitudinal bore and a longitudinal slot communicating with the bore and extending to the outside, a lead in said bore, a follower having a member within said bore, part of said follower extending to the outside, and a separate tubular pusher in said bore, the said follower being received in said pusher intermediate between the ends of the pusher, and being rockable to cause 50 said inner member of the follower to range longitudinally of the bore or to range transversely in said bore in a jammed position.

5. A pencil comprising a sheath having a bore to accommodate a lead, and a longitudinal slot extending from the bore to the outside, a rockable follower having an arm, extending through said slot, and a part within the bore, said inner part having an integral lateral extension wherewith to frictionally engage the wall of the bore, the lateral extension being of greater length than

width and being longitudinally movable in said bore when ranging lengthwise therein, but being adapted to be rocked to range crosswise of said bore in a jammed position 65 to prevent the rearward movement of the lead, the laterally extended part of the follower having a direct frictional contact with the wall of the bore in such jammed position.

6. A pencil comprising a sheath, having a bore accommodating a lead, and a longitudinal slot extending from the bore to the outside, a rockable follower having an arm extending through said slot and a part located within said bore, said inner part having a lateral extension, immovable thereon, whereby to present a total width greater than the slot, and wherewith to frictionally engage the wall of the bore, and an auxiliary pusher slideable in said bore, the said follower engaging the pusher and forming when rocked to a jammed position crosswise of said bore a retaining means for said pusher and lead.

7. A pencil comprising a sheath, having a bore accommodating a lead, and a longitudinal slot extending from the bore to the outside, a rockable follower having an arm extending through said slot, and a part 90 within the bore, said inner part being laterally extended to project beyond the adjacent side wall of the slot, the lateral extension being of greater length than width and being longitudinally movable in said bore when ranging lengthwise therein, but being adapted to be rocked to range crosswise in said bore in a jammed position, the laterally extended part of the follower having a direct frictional contact with the wall 100 of the bore in such jammed position, and an auxiliary pusher having an opening intermediate its ends, through which the laterally extended part of the follower enters the pusher to stand upright therein in the mentioned jammed position, but to lie within the pusher and be enveloped by same when the outer arm of the follower has been rocked to a perpendicular position, said pusher and opening serving to steady the 105 follower and to limit the rocking movement of same while it is being moved forward to advance the lead, the said pusher communicating the forward movement as also the retaining action of the follower to the lead, 110 and the rearward movement of the lead to the follower.

Correction in Letters Patent No. 1,125,890.

It is hereby certified that in Letters Patent No. 1,125,890, granted January 19, 1915, upon the application of Lewis H. Sondheim, of New York, N. Y., for an improvement in "Lead-Pencils," an error appears in the printed specification requiring correction as follows: Page 1, line 17, after the word "characterized" insert the words *functionally by a capability of jamming*; and that the said Letters Patent should be read with this correction therein that the same may conform to the record of the case in the Patent Office.

Signed and sealed this 23rd day of February, A. D., 1915.

[SEAL.]

J. T. NEWTON,

Acting Commissioner of Patents.
